UNITED STATES PATENT OFFICE

CHARLES G. SIGWALD, OF MINNEAPOLIS, MINNESOTA

DESIGN FOR AN OIL BURNER

Application filed September 12, 1932. Serial No. 44,815. Term of patent 7 years.

To all whom it may concern:

Be it known that I, CHARLES G. SIGWALD, a citizen of the United States, residing at Minneapolis, in the county of Hennepin and State of Minnesota, have invented a new, original, and ornamental Design for an Oil Burner, of which the following is a specification, reference being had to the accompanying drawing, forming part thereof.

Fig. 1 is a plan view of the oil burner;
Fig. 2 is a view in side elevation of said oil burner; and

Fig. 3 is a view in rear end elevation of said oil burner.

I claim:

The ornamental design for an oil burner, as shown.

CHARLES G. SIGWALD.
